SUPPORT FOR TILTING A SKILLET HANDLE

Schuylar C. Mowrer, 218 S. Washington St.,
Danville, Ind. 46122

Filed June 27, 1966, Ser. No. 2,833

Term of patent 14 years

(Cl. D44—10)

Fig. 1

Fig. 3

FIG. 1 is a front elevational view of a support for tilting a skillet handle embodying my new design;

FIG. 2 is a side elevational view of the design; and

FIG. 3 is a top plan view of the design.

I claim:

The ornamental design for a support for tilting a skillet handle, as shown.
